UNITED STATES PATENT OFFICE.

WILLIAM C. BUHLES, OF SAN FRANCISCO, CALIFORNIA, ASSIGNEE TO FRANZ BRUCKMANN, SR., FRANZ BRUCKMANN, JE., AND WERNER BRUCKMANN, OF BRUNSWICK, GERMANY, CO-PARTNERS AS FIRM OF BREMER & BRUCKMANN.

SHEET-METAL-SHAPING MACHINE.

1,126,699.

Specification of Letters Patent.

Patented Feb. 2, 1915.

Application filed April 4, 1910. Serial No. 553,252.

To all whom it may concern:

Be it known that I, WILLIAM C. BUHLES, a citizen of the United States, and a resident of the city and county of San Francisco and State of California, have invented certain new and useful Improvements in Sheet-Metal-Shaping Machines, of which the following is a specification.

The invention relates to improvements in apparatus for flanging, crimping, double-seaming or otherwise shaping sheet metal blanks, in which apparatus the blank is to be worked in successive steps over the entire edge by the successive tools.

The principal object of my invention is to provide an apparatus for flanging, crimping, double seaming, or otherwise shaping sheet metal blanks by means of a plurality of disks or tool elements arranged to operate successively on the blank.

A second object of the invention is to provide an apparatus capable of acting on a plurality of blanks at one time and thereby work a great saving in time.

Another object of the invention is to provide an apparatus which is continuous in operation during the successive steps of working the blank.

To these objects the invention consists of an apparatus of the character described provided with a plurality of separately mounted shaping tools for performing the successive operations, and means to move the blanks to contact with the successive tools.

The following description explains at length the nature of one form or embodiment of my invention, and the manner in which I proceed to apply the same in the production of an apparatus for flanging, crimping, double-seaming or otherwise shaping sheet metal blanks, reference being had to the drawings accompanying this specification.

Figure 1 is a plan or top view of an apparatus embodying the principles of my invention. Fig. 2 is a longitudinal vertical section taken through the center of the apparatus. Figs. 3, 4, 5, and 6 show on a larger scale the steps of one form of the operations capable of being performed by the apparatus, the views being vertical cross-sections through the blanks, part of the blanks being broken away to reduce the size of the figures. Fig. 3 shows the position of the blanks as

they are fed into the apparatus, and Figs. 4, 55 5 and 6 show the successive operations performed by the shaping tools. Fig. 7 is a plan or top view of the apparatus showing means for holding the blanks against vertical displacement and for holding the 60 cover to the can. Fig. 8 is a vertical section through one of the guides showing the holding means.

In the drawings I have shown an apparatus which is particularly adapted to crimp 65 and double seam covers on filled can bodies, but it is evident that the apparatus can also be used for flanging can bodies or otherwise shaping sheet metal blanks depending on the shape of the die forming the shaping 70 tool. I, therefore, do not limit myself to an apparatus for performing any given step in the operation of shaping sheet metal blanks as it is evident that various operations may be performed by varying the die face of the 75 shaping tools. The shapes of the various tool elements to perform the various operations are well known in the art, and further description thereof is thought unnecessary.

The various shaping tools are arranged on 80 the successive disks in the order of their operation, and in the apparatus shown in the drawings three shaping tools are employed, each performing one step; the whole operation being completed in three steps. Any 85 number of shaping tools can be employed, however, depending on the number of steps necessary to complete the operation, the number of disks depending on the number of shaping tools.

The apparatus is preferably mounted for operation upon a frame or table 2 provided with legs or supports 3 for holding the table at a sufficient height to allow the driving mechanism to be arranged beneath.

The disks 4, 5, 6 having the shaping tool dies 7-8-9 formed on their circumferences are mounted for rotation above the table 2. These disks are pressed on to or are otherwise securely attached to the shafts 12, journaled in the bearings 13 on the table. These bearings 13 may be made integral with the table or made separate and attached thereto. Rotary motion may be applied to the disks in any suitable manner and in the 100 present instance I have shown bevel gears 14 on the disk shafts 12, meshing with similar gears 15 on a counter-shaft 16, journaled

in the frame. Motion is imparted to the counter-shaft 16 by means of a drive pulley 17 connected to any suitable source of power.

The disks carrying the shaping tools ⁵ forming the successive steps of the operation are arranged to rotate in opposite directions, so that the adjacent faces of each two successive disks move in the same direction at the point of nearest approach.

¹⁰ For the purpose of holding the blanks against the shaping tools and for conveying them to the next tool, I have provided guides 21—22—23 of suitable form and attached to the table 2 in any desirable manner. These ¹⁵ guides 21—22—23 are concentric with the respective disks 4—5—6 and are arranged in such relation to the disks that the blanks are pressed against the shaping tools to accomplish the desired operation. The guides ²⁰ are provided with die faces 7^a 8^a 9^a on their inner surfaces corresponding to the dies 7—8—9 on the respective disks 4—5—6. The blank is rolled over the guide by the rotary motion of the disk, and the oppositely ²⁵ arranged die faces on the guide and disk perform the desired operation. The guides and disks are so arranged that the blank is carried around on one disk and then picked up by the next disk where the successive operation is performed. The disks are preferably made of sufficient circumference so that the blank will make two complete revolutions during the time it is in contact with each disk, but this relation may be altered ³⁰ depending on circumstances of operation.

The centers of the disks may be arranged on a straight line as shown, or upon a broken line, and I do not wish to limit myself to any particular arrangement or spacing of ³⁵ the disk centers. It may be desirable to hold the blank in contact with one disk over a greater arc than with the others owing to the operation being performed. This may be accomplished by placing the center of the disk in such position that the blank could contact with the disk over a greater arc before being taken up by the next disk or by increasing the diameter of the disk.

The blanks are delivered to the apparatus ⁴⁰ at A and are rolled over the guide 21 by the disk 4 until they contact with the guide 22, they are then rolled along the guide 22 by the disk 5 until they contact with the guide 23 and are conveyed by the action of the disk 6 to the runway 25 whence they are delivered from the machine.

During the travel of the blanks around the disks, suitable holding means, such as ⁴⁵ illustrated in Figs. 7 and 8, are employed to hold the blanks against vertical displacement or to hold the covers to the cans. This holding means consists of a holder 31 adapted to seat on the blank or upon the cover of the can. The holder is provided with a neck ⁵⁰ 36 in which is seated a ball 32 which is revolu-

ble in its socket. Arranged over the runway between the disks and the guides and secured to the guides is the plate 33 which is provided with a groove 34 in which the ball 32 travels as the blank is advanced by the ⁷⁰ disks. The groove 34 is concentric with the disks and is arranged midway between the disks and the guides, so that the blank is held in the proper position. The blanks or cans are fed into the machine by the star ⁷⁵ wheel 35 and the holders move along the tracks 36 and drop onto the can in the star wheel. The neck of the holder is provided with a groove 37 for engaging the tracks 36. The tracks receive the holding means as the ⁸⁰ can passes out of the machine and it is moved along the track by suitable means and again deposited on the can entering the machine. The movement of the star wheel ⁸⁵ 35 and the holders is timed so that the holder will be deposited on the can while it is being held at rest by the star wheel. This is but one form of holding means which may be employed, and I do not limit myself to the use of this particular holding means since it ⁹⁰ forms no part of the present invention.

For the purpose of illustrating one series of operations which the apparatus is capable of performing, I have shown in Figs. 3, 4, 5 and 6 the various steps in crimping and ⁹⁵ double-seaming a cover 26 to a flanged can body 27. Fig. 3 shows the can as it is fed into the apparatus, the cover 26 provided with a downwardly depending flange 28 being placed on the can. The disk 4 performs the operation shown in Fig. 4 where-in the flange 28 has been crimped against the flange 29 on the can body. The second operation performed by the disk 5 consists in bending the crimped portion at an acute ¹⁰⁵ angle to the can body, and the third operation performed by the disk 6 presses the crimped portion against the can body forming a double-seam. It is to be understood, however, that I do not limit myself to such ¹¹⁰ a series of operations as shown, as other operations could be performed depending on the dies of the shaping tools. The blanks may be fed into the machine in rapid succession, so that several blanks are always in ¹¹⁵ contact with each disk, thereby maintaining a continual progression of the blanks through the apparatus.

It is evident that as the blanks or can progress through the apparatus and the ¹²⁰ various operations are performed, the can or blank is varied in diameter and the radii of the shaping tools on the disks or the distance between the shaping tools on the disks and the guides must be varied to accommodate ¹²⁵ this change in diameter.

Inasmuch as the principal feature of my invention is the use of a series of disks having fixed axes and provided on their peripheries with tool elements for working or ¹³⁰

shaping the blank, and as means for holding the blanks in contact with the tools, and means for moving the blank from one tool to the other are old and well known in the art, I do not desire to limit myself to the guiding and conveying means shown, as any other well known means may be employed for performing this function.

Many other changes could be made in the apparatus as shown and described without departing from the spirit of my invention, which I wish to be construed broadly as set forth in the claims at the end of this specification.

15 I claim:

1. In an apparatus of the character described, the combination of a plurality of disks having shaping tools formed on their circumferences, a guide extending partly around each disk and being spaced apart therefrom and concentric therewith, said guides and disks forming a tortuous passage, a shaping tool on each guide corresponding to the shaping tool on the coacting disk and means for rotating the disks.

2. In an apparatus of the character described, a plurality of disks having shaping tools formed on their circumferences adapted to perform the successive steps in working the blank, the successive shaping tools being formed with increasing radii, means for holding the blanks in contact with the tools and means for rotating the disks.

3. In an apparatus of the character described, a plurality of disks arranged to rotate about fixed axes, said disks lying in one plane and being spaced apart from each other, shaping tools adapted to perform the successive steps in working the blank formed on the circumferences of the successive disks,

means for rotating the disks, means for holding the blank against the tools and means for guiding the blank to the successive disks.

4. In an apparatus of the character described, a plurality of disks arranged to rotate about fixed axes, shaping tools for performing the successive operations in shaping the blank arranged on the successive disks, guides to hold the blanks against the shaping tools arranged concentric to said disks, the blanks being advanced by being rolled by the tools along said guides.

5. In an apparatus of the character described, a plurality of disks arranged a fixed distance apart and adapted to rotate in a horizontal plane, shaping tools formed on the circumferences of said disks, guides spaced apart from said disks and arranged concentrically therewith and a table below the disks for supporting the blanks.

6. In an apparatus of the character described, a plurality of disks arranged a fixed distance apart and adapted to rotate in a horizontal plane, shaping tools for performing the successive operations in shaping the blank arranged on the successive disks and means for guiding and holding the blank against vertical displacement.

7. In a can seaming machine, a plurality of pairs of relatively movable curved forming members, and means for actuating said members whereby the can is rolled between said members and the edge of its cap is successively bent into a predetermined shape, substantially as described.
